CIRCUIT CONTROLLER

Herbert L. Bone, Forest Hills, Pa., assignor to
The Union Switch & Signal Company, Swiss-
vale, Pa., a corporation of Pennsylvania

Application January 19, 1942, Serial No. 427,279

3 Claims. (Cl. 200—67)

My invention relates to circuit controllers, and more particularly to circuit controllers for use with an operated member having a limited angular movement.

An operated member is frequently biased by gravity or other means to a first position and is motor driven to a second position spaced a pre-determined angular movement from the first position. For example, a highway crossing gate at the intersection of the railway and highway is often biased by gravity to an obstructing position where the gate arm extends horizontally across the highway to obstruct highway traffic entering the intersection, and is motor operated to a clear position where the gate arm is vertical to clear highway traffic. The motor is automatically deenergized in the clear position and a holding magnet is energized to latch the gate arm at such clear position. When a train approaches the intersection the holding magnet is deenergized and the gate arm gravitates to its horizontal position.

An object of my invention is the provision of a novel and improved circuit controller for governing the actuating motor of an operated member having a limited angular movement.

A further and peculiar object of my invention is the provision of a novel circuit controller of the snap switch type for governing the motor of a highway crossing gate. Such circuit controller is interposed in the motor circuit and is actuated to open the motor circuit when the gate arm reaches its clear position, and then is actuated to reclose the motor circuit only after the gate arm has been lowered a predetermined number of degrees from the clear position.

Other objects and advantages of my invention will appear as the specification progresses.

I shall describe one form of apparatus embodying my invention, and shall then point out the novel features thereof in claims.

In the accompanying drawing, Fig. 1 is a view partly diagrammatic and partly in section showing one form of circuit controller embodying my invention when used with a highway crossing gate. Fig. 2 is an end view of certain parts of Fig. 1. Fig. 3 is a fragmentary view showing a position of the cam follower and related parts of Fig. 1. In each of the three views, like reference characters designate similar parts.

It is to be understood that my invention is not limited in its use to highway crossing gates and this one application serves to illustrate the many places where a circuit controller embodying the invention is useful.

Referring to Fig. 1, the reference character G1 designates a highway crossing gate arm which is fixed on a shaft 4, indicated in part conventionally by a dotted line, and which shaft 5 is the operating shaft of the gate mechanism. Such highway crossing gate mechanism may take different forms, and may be, for example, similar in construction to that shown and described in Letters Patent of the United States No. 1,138,087, granted to John P. Soleman on May 4, 1915, for Railway signals, and to which patent reference is made for a full understanding of such mechanism. In the present application, gate arm G1 is an extended form of the semaphore of the patent. It is sufficient for the present application to point out that the gate arm G1 is biased by gravity to a horizontal position, that is, to the position shown by solid lines in Fig. 1, and is motor actuated clockwise substantially 90 degrees to a clear or vertical position as indicated by dotted lines in Fig. 1. In other words, gate arm G1 is an operated member having an arcuate movement limited to substantially 90 degrees. As an aid in understanding the apparatus I shall at times refer to the horizontal position of the gate arm as the zero degree position, and to the vertical position as the 90 degree position.

Shaft 4 is operatively connected to a motor 30 M1 through a gear train 65. As here shown, motor M1 is of the direct current series type, the arrangement being such that when its armature 6 and field winding 7 are energized, the motor is operated as required to drive shaft 4 clockwise, and thus raise the gate arm G1 against its bias to the vertical position. The gate mechanism also includes a pick-up winding PM and a holding winding HM, which actuate a latch means not shown for retaining the gate arm at 35 its 90 degree position, the arrangement being such that energization of both magnets PM and HM is required to pick up the latch armature, but once picked up it is held in position by energization of the holding winding HM only. The gate mechanism further includes circuit controller contacts operated by the shaft 4, and of which circuit controller contacts two are shown conventionally at 3 and 5, while a third is indicated as a whole by the reference character 40 50 CC. This circuit controller CC embodies my invention, and its structure will now be described.

A cam member 9 is firmly secured to shaft 4 by any suitable means, such as a clamp 10, and is disposed on the shaft to occupy the position 55 shown in Fig. 1 when the gate arm G1 is at its

horizontal or zero degree position, and is rotated clockwise 90 degrees along with shaft 4 when the gate arm is raised to its vertical or 90 degree position. When the gate arm G1 gravitates back to its zero degree position, then cam member 9 is of course actuated back to the position shown in Fig. 1. Cam member 9 is formed with a periphery 11, the arc of the effective portion of which is a preselected number of degrees less than the 90 degree arcuate movement of the gate arm. For example, the arc of the effective portion of periphery 11 may be about seven degrees less and substantially 83 degrees. At the upper or left-hand end as viewed in Fig. 1, periphery 11 of cam member 9 is bifurcated, the two bifurcations 40 and 41 (see Fig. 2) each having a beveled surface 43 and a stop surface 42 into which the periphery 11 terminates. The radius of periphery 11 is immaterial and may be of any suitable dimensions.

A drag link 12 is pivotally mounted at its lower or inner end on cam member 9 by means of a pin 13 which is journaled in bearings cast integral with cam member 9. The upper and outer end of drag link 12 lies between bifurcations 40 and 41 and is formed with a periphery 15 which aligns and forms a continuation of the periphery 11 of cam member 9. At the left-hand edge of the drag link periphery 15 there is formed a beveled surface 16 which terminates in a latch surface 17. It is clear that drag link 12 can be rotated about pivot pin 13 relative to cam member 9 and is of course actuated along with cam member 9 when shaft 4 is rotated. The upper or left-hand rotation of drag link 12 about pivot pin 13 is limited by a stop pin 18 mounted in the bifurcations 40 and 41. The downward or right-hand rotation of drag link 12 about pivot pin 13 is controlled by spring means comprising a spring bolt 21 and a relatively light tension spring 19. Spring bolt 21 is mounted in a bore of a boss 24 cast on cam member 9, a spring 20 of relatively strong tension being placed on bolt 21 and confined between a shoulder of the bolt and the bottom of the bore to force the bolt 21 outward. Such movement of spring bolt 21 is adjusted by a nut 26 and the parts are so arranged that the curved surface of the bolt head 27 of spring bolt 21 is made to normally clear drag link 12 by a predetermined clearance of the order of say one-eighth inch. The relatively light tension spring 19 is mounted in drilled holes of the drag link 12 and bolt head 21. Thus drag link 12 is rotatable about pivot pin 13 between stop pin 18 and the spring bolt 21.

A spring contact member 30 is fixed at its lower end by terminal bolt 31 secured in a terminal block 32 of suitable insulation material. The free end of contact member 30 is formed with a flexible contact 34 adaptable of engaging a stationary contact 35 which is secured by a terminal bolt 36 in a terminal block 37 of suitable insulation material. Hence when spring contact member 30 is forced to the right to the position shown in Fig. 1 to bring flexible contact 34 into engagement with stationary contact 35, an electrical connection is completed between terminal bolts 31 and 36. Spring contact member 30, however, is of relatively stiff material and is biased to the left where its flexible contact is out of engagement with stationary contact 35.

A cam follower 38 is mounted on spring contact member 30 by means of insulation strips 39 and screws 40a, making cam follower 38 electrically insulated from spring contact member 30.

but operatively connected thereto. The parts are so disposed that cam follower 38 rides on peripheries 11 and 15 and forces contact member 30 to the right to close the contact 34-35.

The operation and function of circuit controller CC can best be understood by a description of the apparatus as a whole. The control circuits for the gate mechanism may be any one of several well-known arrangements, and as here shown, these circuits are controlled by a control relay R1 which in turn may be governed manually or automatically by railway traffic moving over the intersection of the railway and highway at which the gate mechanism is located. In Fig. 1, the gate mechanism is shown as occupying the zero degree position and to operate the gate arm G1 to the 90 degree position, the control relay R1 is picked up to close front contacts 51 and 52. The closing of front contact 51 completes a motor operating circuit comprising terminal B of any suitable source of current, such as a battery not shown, front contact 51 of relay R1, contact 34-35 of circuit controller CC since cam follower 38 now rests on periphery 11 of cam member 9, wire 53, winding of a relay SR to be referred to later, armature 6 and field winding 7 of motor M1 and terminal C of the current source, and motor M1 is energized to drive shaft 4 and gate arm G1 in the clockwise direction. When 83 degrees of the movement of the gate arm is completed, cam follower 38 rides off periphery 11 of cam member 9 onto periphery 15 of drag link 12, but drag link 12 is prevented from rotating about the pivot pin 13 by stop pin 18. At the 89 degree position of the gate arm, that is, at substantially the 90 degree position, cam follower 38 moves off periphery 15 onto the beveled surface 16 of the drag link. Since spring contact member 30 is of relatively stiff material and is biased to the left the force of contact member 30 rotates drag link 12 about pivot pin 13 against the light tension of spring 19 and the electrical contact 34-35 is opened with a snap action. Cam follower 38 pushes drag link 12 down against the tension of spring 19 and comes to stop against the stop surface 42 of cam member 9 and in which position it also engages the latch surface 17 of drag link 12. The opening of the motor circuit deenergizes the motor and rotation of the shaft is stopped. Circuit controller contact 3 is closed at about the 86 degree position of the movement and current flows over the motor circuit up to wire 53 and thence over contact 3 and the winding of pick-up magnet PM to terminal C of the current source during that portion of the movement between 86 degrees and 89 degrees. The closing of front contact 52 of control relay R1 completes an obvious circuit for holding magnet HM and consequently energization of the pick-up magnet PM at the 86 degree position causes the latch armature to be picked up so that when the contact 34-35 is opened by the action of controller CC as explained above, the gate mechanism is latched at the 90 degree position by energization of the holding magnet HM. The gate arm G1 is then retained at the 90 degree or vertical position as long as control relay R1 remains energized to close the circuit for the holding magnet HM. It is to be noted that at this 90 degree position the hook end of cam follower 38 engages both the stop surface 42 of cam member 9 and latch surface 17 of drag link 12.

To lower the gate arm, the control relay R1 is deenergized and upon releasing opens front contact 52 to deenergize the holding magnet HM.

with the result that the gate mechanism is driven back toward its zero degree position by the bias force of the gate arm. As cam member 9 rotates counterclockwise away from the 90 degree position, the cam follower 38 which now engages latch surface 17 of drag link 12 pulls drag link 12 clockwise about pivot pin 13, first against the light tension of spring 19 and after the one-eighth inch clearance between the drag link and the head 27 of spring bolt 21 is taken up, against the relatively strong resistance of spring 20. This operation of rotating drag link 12 about the pivot 13 to compress spring 20 continues as the cam follower 38 rides up the beveled surface 43 of cam member 9 and is forced outwardly. As best shown in Fig. 3 when cam follower 38 has moved up beveled surface 43 a preselected distance it slips off the latch surface 17 of drag link 12 onto the beveled surface 16. Surface 16 is so sloped that the effort of spring 20 of spring bolt 21 drives drag link 12 upwardly to force cam follower 38 to the right against the force of spring contact member 30 to close contact 34-35 with a snap action. The parts are so arranged that this reclosing of contact 34-35 takes place at about 7 degrees away from the 90 degree position whereas the contact 34-35 was opened at about 89 degrees in the movement toward the 90 degree position. With contact 34-35 closed, the motor circuit is prepared for energization of motor M1 whenever the control relay R1 is picked up, and hence operation of the gate arm back toward its 90 degree position can be effected at any point after the 83 degree position is reached. From the foregoing description it is clear that the circuit controller CC is actuated to open the motor circuit with a snap action just before the full 90 degree position is reached and then is actuated to reclose the motor circuit only after a preselected number of degrees in the movement away from the 90 degree position.

It is to be observed that the friction of cam follower 38 of the drag link 12 may be sufficient to force the drag link against stop pin 18 and the light tension spring 19 may not be required.

It is also to be pointed out that relay SR is in series with the motor M1 and hence is energized and picked up whenever the motor is energized to drive the gate arm toward its clear position. However, when the gate arm gravitates back to its zero position and motor M1 is driven through the gear train, the relay SR is released closing back contact 55. The controller contact 5 is adjusted to close its contact at some predetermined position in the downward movement of the gate arm, and contact 5 when closed completes a low resistance circuit path for motor M1 which low resistance circuit path can be traced from the right-hand terminal of motor M1 over back contact 55 of relay SR, controller contact 5, resistor R3 and to the left-hand terminal of motor M1. Thus when motor M1 is driven by the lowering of the gate arm, it acts as a generator and cushions the downward movement.

I have found that a circuit controller of the structure here disclosed and described provides a very satisfactory and reliable operation for the motor circuit of a highway crossing gate.

Although I have herein shown and described but one form of circuit controller embodying my invention, it is understood that various changes and modifications may be made therein within the scope of the appended claims without departing from the spirit and scope of my invention.

Having thus described my invention, what I claim is:

1. In combination, a shaft having a reversible arcuate movement between a first and a second position, a cam member fixed on said shaft and formed with a periphery which terminates at one end in a beveled surface, a drag link pivoted on said cam member and formed with a periphery that aligns with the cam member periphery at said one end, said drag link periphery terminating in a beveled surface and then a latch surface at its end remote from the cam member periphery, a stop to limit rotation of said drag link about its pivot away from said cam member periphery, spring means to oppose rotation of the drag link about its pivot toward said cam member periphery and characterized to exert a strong force only after the link has been rotated a given angle from said stop, a cam follower spring biased to engage said peripheries and said beveled and latch surfaces; and a circuit controller contact having a stationary member and another member operatively connected to said cam follower to close the contact when the cam follower engages said peripheries, to open the contact by snap action as said shaft moves toward said second position due to rotation of the drag link about its pivot by the spring bias of the follower when the follower engages the beveled surface of the drag link, to hold open the contact at said second position, to compress said spring means when the shaft moves toward said first position because the follower engages said latch surface, and to close the contact by snap action as said shaft moves toward said first position due to rotation of the drag link about its pivot by said spring means when the cam follower engages the beveled surface of the cam member and is lifted out of engagement with said latch surface.

2. In combination, a shaft having a reversible movement between a first and a second position which are spaced a predetermined number of degrees of a revolution, a cam member fixed on said shaft and formed with an effective periphery of an arc less than said predetermined number of degrees and terminating at one end in a beveled and a stop surface, a drag link pivoted on said cam member and formed with a periphery which aligns with the cam member periphery adjacent said one end, said drag link periphery terminating at its end remote from the cam member periphery in a beveled and a latch surface, a stop to limit rotation of said drag link about its pivot away from the cam member, spring means to oppose rotation of said drag link about its pivot toward the cam member and characterized to exert a strong force only after the link has been rotated a given angle from said stop, a spring contact member fixed at one end and adapted to engage at its free end a stationary contact to complete an electrical contact but biased away from such engagement; and a cam follower mounted on said spring contact member and disposed to ride on said peripheries to close said electrical contact as said shaft moves toward said second position, to engage the beveled surface of the drag link and rotate the drag link about its pivot due to the bias of said spring member to open by snap action said electrical contact at substantially the second position, to engage said stop and latch surfaces at said second position with said contact open, to rotate said link and compress said spring means when the shaft moves away from said second position.

due to the engagement with said latch surface, and to engage said beveled surface of the cam member when the shaft is rotated away from said second position toward said first position to force the cam follower out of engagement with said latch surface and permit said drag link to be rotated about its pivot by said spring means to close by snap action said electrical contact.

3. In combination, a shaft reversibly operated between a first and a second position spaced a predetermined number of degrees of a revolution, a cam member fixed on said shaft and formed with an effective periphery of a preselected number of degrees less than said predetermined number of degrees and terminating at one end in a beveled surface, a drag link pivoted on said cam member and formed with a periphery of an arc substantially equal to said preselected number of degrees, said drag link disposed for its periphery to align with the cam member periphery at said one end and formed with a beveled surface and a latch surface, means including a stop pin and a spring bolt to limit

rotation of said drag link about its pivot away from the cam member and to oppose rotation of the drag link about its pivot toward the cam member, a cam follower spring biased to ride on said peripheries; and a circuit controller contact having a member operatively connected to said cam follower to close the contact when said follower rides on the peripheries, to open the contact by snap action at substantially said second position due to rotation of said drag link about its pivot by the spring bias of the follower when the follower engages the beveled surface of the drag link, to hold open the contact at said second position, to compress said spring bolt when the shaft moves toward said first position due to the cam follower engaging said latch surface, and to close the contact by snap action at a preselected point in the movement of the shaft toward said first position due to rotation of the drag link by said spring bolt when the follower is raised free from the latch surface by the beveled surface of the cam member.

HERBERT L. BONE.
